TYPEWRITING MACHINE

William F. Helmond, West Hartford, Conn., assignor to Underwood Elliott Fisher Company, New York, N. Y., a corporation of Delaware

Application June 22, 1939, Serial No. 280,545

4 Claims. (Cl. 197—73)

This invention relates to typewriting machines and, with regard to certain more specific features thereof, to case-shifting devices particularly of the character in which electromagnetic means is employed in the operation of shifting from one case-typing position to another. In certain respects the invention is an improvement upon that shown and described in my copending application Serial No. 280,546, filed June 22, 1939.

It is a particular object of the present invention to simplify and quicken the controls for the electromagnetic means and the case-shifting connections, as shown in the copending application above referred to.

Other objects of the invention will be in part obvious and in part pointed out particularly as the following description of a preferred embodiment of the invention proceeds.

In the drawings:

Fig. 1 is a view in fore-and-aft section of a typewriter embodying the improved case-shifting mechanism.

Fig. 2 is a view similar to Fig. 1 but illustrating the parts in upper-case typing position assumed when the case-shift key is depressed.

Fig. 3 is a fragmentary view in perspective of the latching mechanism and a portion of the control for the electromagnetic means.

Fig. 4 is a fragmentary plan view showing a portion of the control means for the electric motor and the driving connections from the motor to the case-shift frame.

Referring now more in detail to the drawings, a typewriter frame is indicated generally at 10. It has conventional side walls one of which is indicated at 11 and a rear wall 12. The typewriter carriage is indicated generally at 13 mounted for transverse movement on a way rod 14. The typewriter carriage frame is shown at 15 and between end walls of this frame, one of which is shown at 16, a shaft 17 is mounted having a lift hook 18 at each end. The lift hooks take under pins 20 of a movable skeleton 21 which is also pivotally connected to the carriage frame by end links 22.

A roller platen 23 is suitably journaled in the skeleton and the latter has a roll bearing on a case-shift part or frame 24 as indicated at 25. An adjustable stop 26 is arranged in the path of a shoulder 27 of the skeleton to variably limit the movement of the latter to upper-case typing position.

The shift frame 24 comprises opposite end members 28 and 30 connected by a cylindrical rod 31. The end members are fixed upon a shaft

32 suitably journaled in the side walls of the main frame of the typewriter. The left-hand end member 28 of the shift frame has a laterally extending pin 33 projecting into an aperture 34 at the end of a lever 35 pivotally mounted on the frame by a shoulder screw 36. The forward end of lever 35 has an ear 37 underlying an arm 38 of a case-shift key-lever 40 fixed on the shaft 41 which latter is journaled in the side walls of the frame. A right-hand case-shift key-lever is shown in Fig. 3 at 42 also fixed on shaft 41.

Upon a transverse bar or backbone 43 of the main frame there is fixed a bracket 44 journaling a short rock-shaft 45 which latter has a fixed arm 46 the upper end of which is pivotally connected at 47 to a link 48 and the other end of which is pivotally connected at 50 to the left-hand case-shift key-lever 40. A spring 51, having one end connected to bracket 44 and the other end to link 48, normally urges the link rearwardly and the case-shift lever 40 counterclockwise. This movement is limited by a stop lug 52 of lever 40 abutting a comb plate 53 fixed to the frame of the machine. Spring 51 thus determines the normal or undepressed position of case-shift keys 54 and 55 of levers 40 and 42 respectively. A torsion spring 56 tends to hold lever 35 with its rear end depressed to encompass pin 33 of the case-shift member within a latch portion 57 of aperture 34. Thus the lower-case position of the case-shift frame is determined and maintained until one of keys 54 or 55 is depressed, whereupon arm 38 urges ear 37 downwardly to raise the rear end of lever 35 against the action of spring 56 and withdraw latch portion 57 from the pin 33.

A coil spring 60 has one end anchored to the main frame at 61 and its other end attached to end member 28 of the case-shift frame at 62. Thus as either key is depressed and pin 33 is released spring 60 will swing case-shift frame 24 counter-clockwise, as viewed in Figs. 1 and 2, raising the cylindrical rail 31 and lifting skeleton 21 and platen roller 23 until stop 26 is engaged by shoulder 27 of the skeleton.

An electric motor is indicated at 63 and has an armature shaft 64 upon which are fixed spaced collars 65 and 66. Adjacent collar 65 is a friction disk 67 and next to that a pulley 68 loose upon the shaft 64. On the other side of the pulley is a disk 70 of friction material faced with a loose metal collar 71. A coil spring 72 compressed between collars 66 and 71 develops a surface friction sufficient to rotate pulley 68 with the armature shaft 64 and provides for slip in the

drive when a suitable resistance to the movement of case-shift part 24 is developed.

A belt 73 has one end fixed to pulley 68 and, after passing around an idler pulley 74 mounted on a bracket 75 on cross bar 43, its other end is attached at 76 to an upper part of the case-shift frame 24 near the rail 31. It will be seen that energization of the motor 63 to rotate its armature shaft in a clockwise direction, as viewed in Figs. 1 and 2, will wind the belt on pulley 68 and move case-shift frame 24 clockwise on its shaft pin 32 thus dropping rail 31 and allowing the skeleton and platen to follow. The friction developed by spring 72 plus gravity effect is sufficient to expand or reenergize spring 60 and position pin 33 where it may be latched by lever 35.

At the rear of the machine is a motor control box and motor supporting bracket 77 having several inwardly projecting posts 78 upon which is mounted a vertical plate 80 faced with an insulating plate 81. Along the face of insulating plate 81 is a metal strip 82 of electrical conductivity carrying a fixed contact 83. A yoke 84 extends forwardly from the insulating plate 81 and serves to pivot at 85 a lever 86 carrying at one end a contact 87 engageable with the fixed contact 83. Lever 86 has a depending tail 88 against which an arm 90 fixed on the case-shift frame 24 at 91 bears when the frame is in its latched lower-case typing position. A leaf spring 92 having its lower end fixed to insulating plate 81 bears against the opposite side of tail 88 and tends to urge contact 87 into engagement with contact 83 when the case-shift frame is moved to upper-case typing position by spring 60. This engagement is temporarily prevented, however, by a shoulder 93 on a link 94 engaging a portion 95 of an insulating strip 96 which depends from the contact carrying side of lever 86. Link 94 has its forward end pivotally connected at 97 to an arm 98 fixed on rock shaft 45 and the rear end of the link passes through slots in insulating strip 96, insulating plate 81 and vertical metal plate 80. The link is recessed to provide the shoulder just described and normally this shoulder is somewhat to the rear of insulating strip 96.

Thus when either of the case-shift keys is depressed link 48 is drawn forwardly rocking shaft 45 and drawing forwardly the link 94 so that when the latch pin 33 has been released and the case-shift part 24 swung by spring 60 to remove arm 90 from contact carrying lever 86, the shoulder 93 will engage portion 95 of insulating strip 96 and withhold the contacts from engagement against the action of leaf spring 92. This condition will be maintained as long as either case-shift key is held depressed but when the key is released and is on its return to normal position link 94 will move rearwardly allowing leaf spring 92 to cause engagement of contacts 87 and 83 whereupon the electric motor will be energized through suitable circuit connections, including the contact pair 83-87, and move the case-shift frame clockwise, as viewed in Figs. 1 and 2.

By reference to Fig. 2 of the drawings it will be seen how link 94 maintains the contact pair separated during the depression of the case-shift key. It will also be obvious from this figure that the case-shift key may be well on its way back to normal position before the contacts are engaged. Shortly before the point of full return of the case-shift frame to normal or lower-case typing position, the arm 90 again picks up tail 88 of contact-carrying lever 86 and moves it against the opposition of leaf spring 92 to disengage the

contact pair 87-83. Weight of the parts and momentum continue the stressing of spring 60 and the movement of the case-shift frame 24 to its limit of movement determined by engagement 5 of the pin 33 with the end of aperture 34 in lever 35, at which time spring 56 will snap the latch portion 57 of the lever into position over the pin. Fig. 1 of the drawings shows another shouldered link 100 for controlling another contact pair 101-102, the action of which need not be considered for the purposes of the present case.

Conventional case-shift-lever locking means (not shown in the drawings) may be employed for maintaining the case-shift frame in upper-case typing position.

By the mechanism herein described the electric motor circuit controls are simplified over the controls shown and described in my copending application hereinbefore referred to. The shifting of the case-shift frame to upper and lower case typing positions is more direct and speedier than in the mechanism of said copending application, and short pivoted key levers may be employed for controlling the shift action in both directions.

What is claimed is:

1. In a typewriter, a case-shift mechanism comprising, a part to be shifted, spring means for moving said part in one direction, an electric motor for moving said part in the opposite direction, 20 an electric circuit including said motor and a pair of contacts urged to engage, means on the part to be shifted normally holding said contact pair separated, a latch-lever normally holding the part to be shifted against the action of said 25 spring means, a key-lever for operating said latch-lever to release said part to the action of the spring means, a draw-rod connected with said key-lever, having a portion adapted to prevent engagement of said contact pair when the key-lever is moved in one direction to cause release of said part and permitting engagement of said pair to energize said motor when said part has shifted and the key-lever is moved in the opposite direction, and means connecting said motor with said part to move the latter in opposition to said spring means.

2. In a typewriter, a case-shift mechanism comprising, a part to be shifted, spring means for moving said part in one direction, a latch normally holding said part against the action of said 50 spring means, an electric motor, means connecting said motor to said part to move the part in the opposite direction comprising a friction drive device and a belt extending from said device to said part to be shifted, a controlling key, means responsive to the movement of said key in one direction for releasing said latch, and means responsive to the movement of said key in the opposite direction for rendering said motor effective.

3. In a typewriter, a case-shift mechanism comprising, a part to be shifted, a key, means operative upon movement of said key to shift said part in one direction, an electric motor for shifting said part in the opposite direction, and controlling means for said electric motor including a normally open electric circuit, a lever having a contact for closing said circuit, spring means urging the lever in circuit closing direction, a member on the part to be shifted normally engaging said lever to hold it against the action of said spring means, and a draw bar connected to said key normally ineffective on said lever but adapted with lost motion to act on said lever to prevent closing of the circuit by said contact when the said part is shifted pursuant to move-

ment of said key, and spring means for restoring said key upon its release and moving said draw bar to release said lever and allow circuit closing by said contact.

4. In a typewriter, a case-shift mechanism comprising, a part to be shifted, a key, means operative upon movement of said key to shift said part in one direction, an electric motor for shifting said part in the opposite direction, controlling means for said electric motor including a normally open electric circuit, a lever having a contact for closing said circuit, spring means urging the lever in circuit closing direction, a member on the part to be shifted normally engaging said

lever to hold it against the action of said spring means, and a draw bar connected to said key normally ineffective on said lever but adapted with lost motion to act on said lever to prevent closing of the circuit by said contact when the said part is shifted pursuant to movement of said key, spring means for restoring said key upon its release and moving said draw bar to release said lever and allow circuit closing by said contact, and means for automatically latching the part to be shifted when the circuit is closed, the motor energized, and the said part shifted in the opposite direction.

WILLIAM F. HELMOND.
